LID CLAMP FOR CONTAINERS

Albert Bober, New York, N. Y.

Application July 24, 1947, Serial No. 763,359

2 Claims. (Cl. 224—45)

1

This invention relates to an improved holder for cans, pails and containers.

The invention relates more particularly to holders for paint cans, and involves a construction wherein companion jaws engage and hold the opposite sides of the rim of the can or container and have bars slidably adjustable on each other by means of loops provided with hand holds for moving the loops apart or toward each other, and are held in adjusted position by means of a clamp which secures the bars against accidental sliding, the clamp being equipped with a handle for lifting and carrying the can or container.

One of the objects of the invention is to provide a holder for paint cans and other containers with hooked end jaws and bars slidable on each other by means of terminal loops so arranged that a non-binding adjustment of the bars can always be made, and to provide a handle with means for clamping the bars by merely turning the handle.

Another object of the invention is the provision of a holder of this type with sliding bars having outer can gripping terminal bars, with coupling loops for holding the bars in sliding relation to each other, and a handle on each coupling loop, which aids in the rapid and easy adjustment of the bars.

Another object of the invention is the provision of a holder for paint cans and other containers having sliding bars provided with terminal jaws and a handle having a loop which encloses both bars and is itself constructed to clamp the two bars against relative sliding movement by a screw action through the loop.

A further object of the invention is to improve the terminal jaw construction of each holding bar, so that the bars will not be displaced at dead center position on the can.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view, showing the improved holder attached to a paint can.

Fig. 2 is an enlarged perspective view, showing the terminal jaws moved inwardly to the limit of their travel toward each other.

Fig. 3 is a transverse vertical cross sectional view, taken on line 3—3 of Fig. 2, looking in the direction of the arrows.

2

Fig. 4 is a partial longitudinal vertical cross sectional view, taken on line 4—4 of Fig. 2, looking in the direction of the arrows.

Fig. 5 is a perspective view of a modified form 5 of the invention, showing a bail on the handle.

Fig. 6 is a detail bottom plan view, enlarged, of one of the terminal jaws of the holder shown in Fig. 5.

The holder of the present invention, is to be 10 used with a conventional paint can or other container 10 having an outwardly directed rim or flange 11 on its upper end.

The holder, according to the form of the invention shown in Figs. 1 to 4, includes flat metal 15 bars 12 and 13 of similar construction. The bar 12 is formed with an outer terminal hook 14 and is equipped on its inner end with a band loop 15, which encloses the body of the bar 13. The inner loop 15 is formed with a struck up flange 16 on which the handle 17 is mounted by means of the cross pins 17a, the handle 17 being of channel construction to receive the flange 16.

The bar 13 is formed with an outer terminal hook 18 and at its inner end is provided with 25 a band loop 19 which slidably receives the body of the bar 12. This loop is also formed with a struck up flange 20, which is received by the channel handle 21, and this handle is secured in place by means of the cross pins 22, which extend through the handle and flange.

Between the coupling loops 15 and 19 a handle 30 loop 23 is disposed, which slidably receives the bars 12 and 13, and limits the inward movement of the loops 15 and 19 toward each other. The loop 15 is positively secured to its bar 12 by brazing or other means, and the loop 19 is positively secured to the bar 13 by brazing or other means. But the loop 23 is slidably mounted on the bars 12 and 13, so that it will not interfere with the 35 sliding of the bars 12 and 13 relative to each other.

The handle loop 23 is provided with an upstanding internally threaded boss or nut 24, which receives an externally threaded screw shank 25 of a T-shaped post 26, which is equipped with a channel-shaped handle 27, secured thereto by the cross pins 28.

The inner end of the screw shank 25 is adapted to have pressure engagement with the uppermost 40 holder bar 12, and when the handle 27 is manually turned, the pressure of the shank 25 against the bar 12 will force this bar against the lowermost bar 13, thereby effectively clamping the two bars against accidental sliding movement.

55 When it is desired to adjust the spacing be-

tween the terminal hooks 14 and 18, the screw shank 25 is loosened by turning the handle 27 upwardly, and then the handles 17 and 21 are grasped and the bars 12 and 13 are shifted relatively to each other to bring the terminal hooks into engagement with the can or container to be handled. The handle 27 is then turned downward and the two bars 12 and 13 will be effectively clamped against each other and the hooks 14 and 18 held in gripping position against the opposite sides of the rim 11 of the container 10.

In Figs. 5 and 6, there is shown a modified form of the invention, wherein the handle 27^a is provided with a C-shaped carrying bail 30 having its confronting terminals 31 and 32 pivotally mounted in the handle 27^a. Each of the bars 12^a and 13^a is provided with a bifurcated terminal hook jaw 33, which permits the positioning of the terminal jaws across the can or container, so that the hooks 33^a and 33^b of the terminal jaws may be placed on opposite sides of the dead center line of the container and accidental slippage thus avoided.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a holder for paint cans and the like having a pair of bars with their inner ends overlapped and their outer ends formed with jaws for gripping the top rim of a can, means for adjustably securing together the adjacent inner ends of the bars to be adjustable to fit cans of different diameters, comprising a loop slidably engaged about the overlapped inner ends of the bars, an internally threaded boss formed on the portion of said loop which extends across the top face of the topmost inner end of the overlapped inner ends, and a T-shaped post having a cylindrical shank and a cross head, said cylindrical shank being threaded and engaged through said threaded

boss to be tightened against the said topmost inner end to clamp the inner ends against the portion of said loop opposite the portion thereof formed with said internally threaded boss, and an inverted channel-shaped handle secured in position on the cross head of said T-shaped post.

2. In a holder for paint cans and the like having a pair of bars with their inner ends overlapped and their outer ends formed with jaws for gripping the top rim of a can, means for adjustably securing together the adjacent inner ends of the bars to be adjustable to fit cans of different diameters, comprising a loop slidably engaged about the overlapped inner ends of the bars, an internally threaded boss formed on the portion of said loop which extends across the top face of the topmost inner end of the overlapped inner ends, and a T-shaped post having a cylindrical shank and a cross head, said cylindrical shank being threaded and engaged through said threaded boss to be tightened against the said topmost inner end to clamp the inner ends against the portion of said loop opposite the portion thereof formed with said internally threaded boss, and an inverted channel-shaped handle secured in position on the cross head of said T-shaped post, said inverted channel-shaped handle having its ends projected beyond the ends of said cross head, and a C-shaped carrying bail having its ends extended into the projected ends of said inverted channel-shaped handle.

ALBERT BOBER.
